UNITED STATES PATENT OFFICE

ALBERT J. WATLING, OF CHICAGO, ILLINOIS, ASSIGNOR TO WATLING MANUFACTURING COMPANY, OF CHICAGO, ILLINOIS, A CORPORATION OF ILLINOIS

DESIGN FOR A GAME BOARD

Application filed June 8, 1932. Serial No. 44,014. Term of patent 3½ years.

To all whom it may concern:

Be it known that I, ALBERT J. WATLING, a citizen of the United States, residing in Chicago, county of Cook, and State of Illinois, have invented a new, original, and ornamental Design for Game Board, of which the following is a specification, reference being had to the accompanying drawing, forming a part thereof.

The figure is a plan view of a game board embodying my new design.

The article shown has no appreciable thickness.

I claim:

The ornamental design for a game board substantially as shown in the drawing and described.

ALBERT J. WATLING.
